PACKAGING OF LOAF-LIKE BAKERY GOODS

Velma M. Bear, Kansas City, Mo., assignor to
Schulze Baking Company, Kansas City, Mo., a
corporation of Illinois

Application July 31, 1933, Serial No. 683,001

1 Claim. (Cl. 229—87)

These improvements relate to the packaging of loaf-like bakery goods, with special reference to cake in circular or elongated form. Its object is to provide a peculiarly advantageous package for such goods, and, as an improvement over what has been known and used, is directed largely to the overcoming of certain pronounced disadvantages of the older practice.

The bakery product called cake is the loaf-like article cut into slices for table use. It is often quite delicate in its physical properties, often quite soft and yielding, with an embellishment of "icing" or "frosting," and one of the difficult problems of the manufacturer is so to package the goods as to insure reasonably the maintenance of the icing and the cake body in fresh and unmutilated condition until the product reaches the home of the consumer. Because of the fragility of the product such cake has been wrapped by hand, although the harder and tougher kinds have been put through a wrapping machine, especially the elongated forms.

For such hand-wrapping of the fragile variety of cake it has been customary to use thin and flexible regenerated cellulosic sheet material such as the material having the trade name "Cellophane" cut to the desired size of sheet, folding the "Cellophane" about the goods, and then applying a band, in the form of a strip of ordinary paper, around the wrapped article, and securing the ends of the strip together by an adhesive. Such paper bands, not being secured to the "Cellophane" wrapper, easily slipped off of the round forms, highly objectionable for various reasons including this that it permitted the gatherings or folds of the wrapper to open, and it is very difficult to replace such a paper band because of its easy-tearing qualities. One feature of the present improvements contemplates securing the band to the wrapper so as to maintain the wrapper in its folded condition and the band properly upon the goods.

Another disadvantage of the paper band is its likelihood of being torn under ordinary conditions. For example, it is the tendency of purchasers to lift the cake and carry it by the band, which is a desirable way to handle the product if the band be able to stand the strain, to avoid crushing or indenting the loaf or smearing or fingermarking the icing. A feature of these improvements is the provision of a band that not only strongly reinforces the wrapper and holds the folded portions of it securely, but which serves as a strong and unrupturable carrying band which, being secured to the wrapper, enables the cake

to be carried free of the danger of its injury by falling due either to the breakage of the band or the slipping of the loaf out of the confining ring.

Such food articles are sold to a considerable extent on the appearance of the particular unit being offered at the time. It is common experience that if the wrapper and band are unsightly, and the paper bands soil easily, the commodity will probably have to be sold at a sacrifice, if saleable at all. The paper bands are practically ruined by moisture, although the "Cellophane" wrapper may fully protect the contents. Then, with the bands coming off during inspection or prior thereto, and with the folds of the wrapper coming or standing open, the effect upon the customer is bad. The attempt of the shopkeeper or customer to refold the wrapper and reapply the band is usually unsatisfactory, and the net result is disappointment, due entirely to the poor packaging of the product.

Still another bad feature of the paper band is that it does not fit the form snugly but curls up objectionably along its sides. This, together with the common paper adjacent to the shiny "Cellophane", gives the appearance of cheapness and make-shift quality to the package. I emphasize such features because of their effect upon successful commercial practice.

I overcome all of these defects and disadvantages, and others readily to be appreciated by those engaged in the marketing of cake, by providing a band of "Cellophane" or the like around the "Cellophane" wrapper, the band being preferably adhesively secured to the wrapper in the vicinity on the wrapper where gathered and folded and encompassing the gathered and folded portions of the wrapper and holding these portions in place, the band preferably carrying the trademark and such other indicia as may be appropriate. Such a band is exceedingly strong and will not be torn by any kind of handling. It serves as a carrying band, being otherwise desirably unsecured to the wrapper, which will stand all the strain put upon it, and it will not come off during such use or otherwise until deliberately removed. It is preferably transparent where not printed upon, but it may be in colors. Thus the form may advantageously be seen through the band and wrapper. Being of the same kind of material as is the wrapper, the optical effect is that of a properly-finished article—a rich appearance instead of a palpably cheap one. The "Cellophane" band lies closely upon the wrapper and does not curl along its side edges. The printing effects upon the "Cellophane" band are quite dif-

ferent from those of ordinary printing on paper, and are more pleasing. Such a band helps the seal of the package against atmospheric as well as liquid moisture, and is not itself injured by moisture, and it is not easily soiled. Then, too, the band appears almost as an integral part of the wrapper—as a wrapper having the design of a band on it.

In applying the band I make certain departures from the older practice. In the first place, I use a special adhesive because the ordinary adhesives are not suitable for "Cellophane"; but a description of such a special adhesive is not necessary here since they are known and used generally in "Cellophane" work. In the next place I apply the adhesive, certainly in the preferred mode, in such a way as to secure the band to the wrapper as well as to itself.

In the drawing Figures 1 and 3 are top views respectively of two forms of cake packaged according to these improvements;

Figs. 2 and 4 are bottom views of the articles of Figs. 1 and 3 respectively;

Fig. 5 is a bottom view following Fig. 2 with the band lying flat before the end portions thereof are turned over and sealed upon the bottom; and

Fig. 6 is a side elevational view of such a wrapped and banded article.

The application of the thin and flexible transparent "Cellophane" wrapper 10 may be according to usual practice, which means that the cake body is rested on a sheet of the material and an ordinary wrapping operation performed which gathers and folds the material upon itself at opposite ends or sides of the cake body and leaves such gathered and folded material as 11, 11 on the bottom of the article. The band 15 of "Cellophane" or the like may be laid extended on the table as in Fig. 5, and the special adhesive material applied at its ends, as at 16 and 17. The dotted lines in Fig. 5 show how one extending part of the band has been laid over upon the folds 11 and there secured to the wrapper by the adhesive 16. The other end of the band is then similarly laid over, partially overlapping the end portion of

the band already secured to the wrapper, and the adhesive 17 then holds the overlapped parts of the band together. The band is thus secured to the wrapper and to itself to form a complete ring about the wrapped article, and it extends so as to pass over and encompass the gatherings or folds at the ends of the elongated loaf-like article of Figs. 3 and 4, or, if the article be circular, as in Figs. 1 and 2, then so as to encompass the gatherings or folds at opposite sides of the round form. In all instances the band preferably extends longitudinally with and over such gathered and folded parts of the wrapper as those marked 11 appearing at the bottom of the article.

It is apparent that by these means I have made a very important improvement in the packaging of the delicate and fragile article in question, both in the mechanical and functional aspects and in the appearance of the packaged goods, better maintaining the desirable qualities of the goods and overcoming numerous objections and disadvantages of what has heretofore been suggested and used.

I claim:

The combination with a bakery product in loaf-like form having a transparent wrapper of regenerated cellulosic sheet material gathered and folded upon itself at its bottom, of a transparent strong and flexible band of regenerated cellulosic sheet material passing completely around the form outside the wrapper where gathered and folded, the ends of the band being adhesively secured directly one to the other and the band being adhesively secured to the wrapper in the immediate vicinity of the gathered and folded portion of the wrapper, the band being free from adhesion to the wrapper at the sides and top of the form and being of extremely narrow width relatively to the form, whereby the band serves to hold the folds of the wrapper in position and elsewhere on the form serves as a bail while at the same time the form may be seen through the band and wrapper.
